UNITED STATES PATENT OFFICE.

WILLIAM J. SHORTILL, OF MARKDALE, ONTARIO, CANADA.

LEVER-ESCAPEMENT.

1,037,342.

Specification of Letters Patent. Patented Sept. 3, 1912.

Application filed December 22, 1910. Serial No. 598,866.

To all whom it may concern:

Be it known that I, WILLIAM J. SHORTILL, of the village of Markdale, in the county of Grey and Province of Ontario, Canada, have 5 invented certain new and useful Improvements in Lever-Escapements; and I hereby declare that the following is a full, clear, and exact description of the same.

The object of my invention is to devise a 10 lever escapement in which the pallets are attached to the pallet lever between the fork and pallet center, to move across the primitive circle of the escape wheel as the pallet lever oscillates under the impulse of the escape wheel and balance, the escape wheel being provided with escape teeth perpendicular to its side faces to engage with the pallets and control the isochronal intermittent movement of the escape wheel as hereinafter 15 set forth and particularly pointed out in the claim.

For an understanding of the invention reference is to be had to the following description and to the accompanying drawings 20 in which:

Figure 1, is a plan view of my lever escapement showing the general construction and position of the related parts. Fig. 2, is a perspective view of the escape wheel. Fig. 25 3, is a perspective view of the pallet lever and pallets, and Fig. 4, is a diagrammatic view of the lever escapement.

Like characters of reference refer to like parts throughout the specification and drawings.

As my present invention relates only to the escape wheel, pallet lever, and pallets, and to the relative position and movement of the latter with regard to the primitive circle 40 of the escape teeth, it will, therefore, not be necessary to specifically describe any of the other parts of the lever escapement.

The escape teeth a a' , instead of projecting peripherally from the rim of the escape 45 wheel b , project perpendicularly to its side faces, the escape teeth a being on one side of the escape wheel, and the escape teeth a' on the other side. The locking face d of each escape tooth a passes to one side of the escape center c and that of each escape tooth a' passes to the other side of the escape center as shown in Fig. 4. Likewise the angular lines of the lifting faces e of the two sets of escape teeth pass to opposite sides of the

tangential line h drawn from the pallet center j to the primitive circle. 55

I find that satisfactory results can be obtained by arranging each locking face d at an angle of twenty four degrees to a radial line drawn from the escape center to the locking corner d' of the escape tooth, and by arranging each lifting face e at an angle of three degrees to the tangential line h , these angles being taken at the place where the pallets k k' cross the primitive circle. The pallets k k' , attached to the pallet lever i oscillating from the pallet center j , are arranged in two different horizontal planes, as shown in Fig. 3, with sufficient clearance between them for the free revolution of the escape wheel. The angles of the lifting faces l of the pallets correspond with the angles of the lifting faces of the escape teeth, and likewise the angles of the locking faces l' of the pallets correspond with those of the escape 70 teeth. 75

One end of the pallet lever i is provided with a fork m engaging with the impulse pin o of the balance p and the pallets k k' are attached to the pallet lever between the fork and the pallet center to move to the right and left of the primitive circle as the pallet lever oscillates under the impulse of the escape wheel. When the balance is swinging to the right, the impulse pin o engages the fork m moving it through a small arc and turning the pallet lever to the right of the pallet center j . This movement disengages the locking face of the inside pallet k' from the locking face of an escape tooth a' and when the locking faces of the inside pallet k' and the escape tooth a' are disengaged, their lifting faces come into contact, throwing the pallet k' and pallet lever farther to the right, causing the fork of the pallet lever to throw the balance wheel to the limit of the right oscillation, and bring the locking face of the pallet k fully into the path of the next escape tooth a . 90 95

Coincident with the disengagement of the pallet k' and escape tooth a' , the escape wheel moves forward until the locking face of the escape tooth a engages with that of the pallet k , and causes the arrest of the escape wheel until the isochronal swing of the balance moves the pallet lever to the left, disengaging the locking face of the pallet k from that of the escape tooth a and bring-

ing the locking corner k^3 of the pallet k' into position to again engage the next escape tooth a' . The lifting face of the escape tooth a then engages with that of the pallet k , throwing the pallet k and pallet lever farther to the left and causing the fork of the pallet lever to throw the balance to the limit of its left oscillation, the escape wheel then moving forward until the locking face 10 of the next escape tooth a' engages with the locking face of the pallet k' , which is then fully in the path of the escape tooth. During the isochronal oscillation of the balance, the pallets k k' move on parallel arcs intersecting the primitive circle of the escape wheel, one pallet being positioned to engage 15 the next escape tooth on its respective side of the escape wheel, before the lifting face of the other pallet is disengaged from the escape tooth on its respective side.

By providing the escape wheel with two sets of escape teeth and interrupting its rotation by the direct action of two pallets moving unitedly across the primitive circle, I 25 am able to arrange for the escape at a small angle of vibration, and obtain a uniform isochronous movement of the parts.

The pallets k k' move in a plane parallel 30 with the side faces of the escape wheel to provide for the free revolution of the latter between them, and the escape teeth of one side of the escape wheel are staggered with respect to those on the other side, the pitch 35 of both sets of escape teeth being the same, so that the intermittent rotation of the escape wheel will be uniform.

Having thus fully described my invention what I claim as new and desire to secure by Letters Patent is:—

In a lever escapement, a balance having 40 an impulse pin, a pallet lever oscillating from a pallet center and having at one end a fork to engage with the impulse pin, an escape wheel comprising two sets of escape teeth projecting perpendicularly from the 45 side faces of the escape wheel, each escape tooth having a locking face and a lifting face, the locking faces of the escape teeth on one side of the escape wheel passing to one side of the escape center and the locking 50 faces of the escape teeth on the other side of the escape wheel passing to the opposite side of the escape center with the angular lines of the lifting faces of the two sets of escape teeth passing to opposite sides of a tangential line drawn from the pallet center to the primitive circle of the escape wheel, and two 55 pallets attached to the pallet lever between the pallet center and the fork, said pallets being arranged in two different horizontal 60 planes with sufficient clearance between them for the free revolution of the escape wheel, each of the pallets being provided with lifting and locking faces, the angles of which correspond with those of the lifting and 65 locking faces of the escape teeth.

Markdale, 6th December 1910.

WILLIAM J. SHORTILL.
